Primary Examiner — Rosemary K Tarcza*Assistant Examiner* — Nathaniel D. Buckner(74) *Attorney, Agent, or Firm* — Fish & Richardson P.C.(57) **CLAIM**

The ornamental design for a wireless charger, substantially as shown and described.

DESCRIPTION

FIG. 1 is a perspective view of a wireless charger.

FIG. 2 is a top view of the wireless charger of FIG. 1.

FIG. 3 is a bottom view of the wireless charger of FIG. 1.

FIG. 4 is a back view of the wireless charger of FIG. 1.

FIG. 5 is a front view of the wireless charger of FIG. 1.

FIG. 6 is a right view of the wireless charger of FIG. 1.

FIG. 7 is a left view of the wireless charger of FIG. 1; and,

FIG. 8 is a perspective view of the wireless charger of FIG. 1 shown in an environment of use.

The broken lines in the figures depict portions of the article and environmental subject matter which form no part of the claimed design.
